UNITED STATES PATENT OFFICE.

JOHN DE PAOLI, OF NEW YORK, N. Y.

METHOD AND APPARATUS FOR TREATING FEATHERS.

1,111,530.

Specification of Letters Patent.

Patented Sept. 22, 1914.

Application filed November 6, 1913. Serial No. 799,445.

To all whom it may concern:

Be it known that I, JOHN DE PAOLI, a citizen of the United States, and a resident of the borough of Manhattan, city, county, 5 and State of New York, have invented certain new and useful Improvements in Methods and Apparatus for Treating Feathers, of which the following is a specification.

My invention relates to the treatment of 10 plume feathers, particularly ostrich feathers, after they have been washed, bleached, rinsed (dyed if for colored plumes) and starched in the usual course of preparation for the market, and is designed to facilitate 15 and render more effective the process of drying, eliminating the starch and opening up, spreading, and fluffing the component parts of the feather.

As is well known in the art the raw feathers in bunches are first washed in soap and water to remove grease, &c., bleached, rinsed, dyed if for color other than white, and then immersed and gently agitated in a bath impregnated with starch which later penetrates not only between the barbs 20 or vanes (known in the trade as the flues) of the feathers, but also insinuates itself between the fine delicate fibrous "hairs" or lateral protruberances of the barbs and prevents adjacent parts adhering directly to 25 each other during the subsequent manipulation of the feather. Hence the problem is to open up the component parts of the feather and eliminate the starch in the most 30 expeditious and effective manner, which I accomplish by my invention, a distinctive feature of which consists in subjecting the feathers while carried on the periphery of a rotating drum in an inclosed chamber to 35 the action of an air blast in partial vacuum or exhaust as hereinafter more fully set forth,—an incidental feature being the provision of means for arresting and recovering 40 feathers that may become detached in the process.

In the accompanying drawings, which are more or less diagrammatic and symbolical, but sufficient to illustrate the principle involved and the practical application of my 45 invention, Figure 1, represents a sectional elevation; Fig. 2, a plan with parts broken away; and Fig. 3, a detail.

I am aware that heretofore feathers have been attached to rotatable drums and subjected to the action of a rotating flail, which latter it is one of the objects of my invention to dispense with since the flail is liable to tear and disintegrate the delicate fibers which form the most important and attractive portion of the plume. For this reason I open up the feathers and separate the starch therefrom by means of an air blast in lieu of direct mechanical contact or beating as heretofore, the pressure of the air being sufficiently positive to dislodge 55 the starch particles without injury to even the fluff of the feather,—and the dislodged starch being removed and recovered for reuse by means of a partial vacuum which aids materially in the process of opening up, 60 drying and cleansing the feathers. For these reasons I mount the rotatable cylinder or drum D in a casing C, provided with doors c, c, or other suitable means of closure, 65 and connect the rear of the casing with an 70 exhaust flue E which extends to and communicates with an exhaust fan E'.

B is an air blast pipe positioned in the upper part of the chamber formed by the casing and communicating through the conduit b, with the air blast fan B'. The air blast pipe B is situated in proximity to the peripheral surface of the drum D and parallel to the axis thereof, or substantially so, and is formed with a series of holes or 75 nozzles b', on the side nearest the drum to deliver the air under pressure substantially 80 at right angles to feathers upon the periphery of the drum D.

The latter may be constructed in any suitable manner, as by end disks supporting longitudinal slats d, d, which are preferably spaced apart slightly to admit of air circulation. The bunches of feathers, tied in series to cords in the usual way, after the 85 excess of moisture taken up in the starch bath has been drained off by centrifugal force or otherwise, are suspended upon certain slats of the drum by means of snap hooks d' (see Fig. 3) of well known construction, or by any other preferred mechanical expedient, the bunches hanging loose from the suspending cords as heretofore and being free to adapt themselves to 90 95 100

the motion of the drum across which they assume tangential positions substantially at right angles to the longitudinal axis of the drum, the deflectors d^1 , d^2 , d^3 , preventing 5 their assuming radial positions under the centrifugal action. These deflectors must not be considered as beaters in any sense of the word, their only function being to guide and aline the feathers in close proximity to 10 the periphery of the drum as the latter rotates in the direction of the arrow, in which direction it will be noted also that the deflectors incline at an obtuse angle.

The air prior to its injection into the 15 closed chamber and against the feathers on the periphery of the drum, may be heated to any degree expedient to facilitate the drying of the feathers as well as the dislodgment of the starch therefrom; and the air 20 pressure used is adapted to effect this displacement of starch and the drying of the feathers without danger of injury to the delicate fluffy portions of the latter.

As an auxiliary to the air blast, and acting 25 in conjunction therewith, the partial vacuum or exhaust is important in creating an air current which not only increases the efficiency of the air blast, but also abstracts, removes, and collects for re-use the starch 30 eliminated from the feathers,—the discharge passage e , of the exhaust fan E' , being connected for this purpose with a collecting chamber not shown in the drawings and of any desired construction.

35. Feathers of heavier weight becoming detached during treatment are precipitated against the side wall e' , of the flue E , and may be withdrawn through a manhole normally closed by a cover e^2 ; feathers of 40 lighter weight are intercepted by a transverse screen e^3 , in the flue near the exhaust fan E' and may be removed through a manhole closed normally by a cover e^4 .

I have found by practical tests and 45 experimental investigation that ostrich feathers thus treated are much more perfect, more fully opened up, and more attractive in appearance than those which are flailed in the old way. Furthermore the elimination of 50 the starch is complete and the "fluff" expanded to the fullest extent; and all this is accomplished with a saving of time, labor and starch, so that my invention is really an important advance in the art. The use 55 of this method and apparatus not only obviates danger of injury to the feathers but also prevents the contamination of the atmosphere by the starch flour and is hence more healthful and sanitary than the old method.

60. What I claim as my invention and desire to secure by Letters Patent is,

1. The method herein described of treating starched feathers for the purpose designa-

nated, consisting in subjecting them while supported on the periphery of a rotating drum to an exteriorly-applied forced air blast only substantially as set forth.

2. The method herein described of treating starched feathers for the purpose designated, consisting in subjecting them while supported on the periphery of a rotating drum in an inclosure to an exteriorly-applied forced air blast only substantially as set forth.

3. The method herein described of treating starched feathers for the purpose designated, consisting in subjecting them to an exteriorly-applied forced air blast only while supported on the periphery of a rotating drum in an inclosure connected with an air exhaust substantially as set forth.

4. In apparatus of the character designated the combination of a rotatable perforated drum, means for supporting feathers on the periphery thereof, and means for directing an air blast only against the periphery of said drum and against the feathers and through the perforation of the drum substantially as set forth.

5. In apparatus of the character designated, the combination of a rotatable perforated drum, means for supporting feathers on the periphery thereof, an inclosure for said drum, and means for directing a blast only of air against the periphery of said drum and against the feathers and through the perforations of the drum substantially as set forth.

6. In apparatus of the character designated, the combination of a rotatable perforated drum, means for supporting feathers on the periphery thereof, an inclosure for said drum, means for exhausting air from said inclosure, and means for directing a blast only of air against the periphery of said drum and against the feathers and through the perforations of the drum substantially as set forth.

7. In apparatus of the character designated, the combination of a rotatable drum, means for supporting feathers on the periphery thereof, an inclosure for said drum, means for exhausting air from said inclosure, a flue connecting said exhaust means with said inclosure, a screen in said flue, a man-hole and cover adjacent thereto, and means for directing a blast of air against the periphery of said drum, substantially as set forth.

8. The method herein set forth of treating starched feathers for the purpose designated, consisting in subjecting them to a forced air blast only substantially as set forth.

9. The method herein set forth of treating starched feathers for the purpose designated, consisting in treating them to the simulta-

neous action of an exteriorly-applied forced air blast only and an exhaust substantially as set forth.

10. Apparatus of the character designated comprising a support for the starched feathers, an inclosure for same, means for loosely suspending the feathers upon the exterior

of said support an air blast only against said support, and an air exhaust connected with said inclosure, substantially as set forth.

JOHN DE PAOLI.
